UNITED STATES PATENT OFFICE.

ANDREW JOHNSON STEWART, OF LEBANON, INDIANA, ASSIGNOR TO CAMPBELL-SMITH-RITCHIE CO., OF LEBANON, INDIANA, A CORPORATION OF INDIANA.

COMBINATION KITCHEN CABINET AND IRONING BOARD.

Application filed June 21, 1922. Serial No. 569,915.

To all whom it may concern:

Be it known that I, ANDREW JOHNSON STEWART, a citizen of the United States, residing at 309 W. North Street, Lebanon, in the county of Boone and State of Indiana, have invented a certain new and useful Improvement in Combination Kitchen Cabinets and Ironing Boards, of which the following is a full, clear, concise, and exact 10 description, reference being had to the accompanying drawings, forming a part of this specification.

My invention relates to combination furniture and pertains more particularly to an 15 improved combination kitchen-cabinet and ironing-board.

An object of my invention is the provision of an improved furniture combination comprising a kitchen-cabinet and an ironing-board 20 so connected thereto that it may be arranged and firmly supported, for use, over the top or horizontal supporting surface of the cabinet, and quickly and conveniently 25 swung from position for use over said surface and out of the way, when not in use, so as not to interfere with access to or the use of the cabinet.

Another object is the provision of an improved connection between the cabinet and 30 the board and an improved mounting of the board to the above ends.

Further objects are to facilitate swinging 35 of the board into and out of position for use; to provide for firmly and rigidly supporting the board for use over the top or supporting surface of the cabinet and to provide such a mounting for the board that it will not be subject to accidental displacement from the position into which it is 40 swung when not in use.

A further object is the provision of a compact combination kitchen-cabinet and ironing-board which shall be of novel construction and simple and convenient to use in 45 either connection.

Still further objects and advantages and the novel arrangement and structural features will appear from the following detailed description and the claims taken with 50 an inspection of the accompanying drawings in which;

Figure 1 is a perspective view of a combination kitchen-cabinet and ironing-board embodying my invention, showing the board

supported for use over the top or horizontal 55 supporting surface of the cabinet;

Fig. 2 is a fragmentary vertical section taken through the board receiving compartment on the line 2-2 of Figure 5 showing the pivotal mounting of the board in section 60 and the adjacent end of the cabinet in elevation;

Fig. 3 is a top plan view of the ironing-board;

Fig. 4 is a front elevational view of the 65 same; and

Fig. 5 is an enlarged perspective view of the board receiving compartment from the front showing the door provided for closing 70 the same.

In the embodiment selected for illustration, the cabinet comprises an enclosed base 5 suitably partitioned or divided up into a base cupboard 6 and a plurality of drawers 7. The base 5 is provided with suitable framework 8 at its respective corners, the lower ends of which form supporting legs for the cabinet. A top 9 is arranged horizontally over the top of the framework of the base and forms the usual top or working 75 surface of the cabinet. It is to be understood that the top 9 may be provided with a suitable covering 10 as shown, or it may be made of porcelain or finished like the rest of the cabinet, or in any other manner as 80 desired.

An upright framework 11 mounted above the rear portion of the top 9 through suitable bracket members 35 provides with the partitions, shelves and doors shown, additional compartments for dishes, packages, jars, etc. The particular compartment arrangement of the cabinet may, of course, be varied, the drawings showing the compartment arrangement in one particular style of 85 combination kitchen-cabinet and ironing-board as it is now being manufactured.

The bottom of the upright framework 11 is provided with a base board 12 which extends horizontally over the rear portion of the top 9. A horizontal shelf 13 carried by the framework 11 is arranged parallel with the baseboard 12 and spaced vertically upwardly therefrom to define a compartment 14 within which and between the base board 12 and shelf 13 the ironing-board 15 is pivotally journaled upon the shank of a bolt 16. The head of the bolt 16 engages in a 100 105

2
recess provided therefor in the upper surface of the shelf 13. The shank extends through the shelf 13 through an opening 17 in the board 15 and into and is secured in 5 the base board 12, or it may extend through the same and be threaded into a nut 18 as shown in Figure 2, or be otherwise secured in place.

While the shape of the board as shown is 10 preferable in this particular embodiment, obviously the board per se may be shaped as desired. A block 19 cut out at one end as shown at 20 to facilitate grasping the same is provided with a pair of angularly 15 projecting dowel pins 21 for insertion into holes in the front edge of the board 15 to detachably secure the block 19 thereto. The block 19 is adapted to be conveniently grasped when the board is in its normal position 20 within the compartment 14 as shown in full lines in Figure 2 and the board swung through a horizontal plane out into horizontal position over the top 9 as shown in full lines in Figure 1 and in dotted lines in Figure 2. The block 19, the thickness of which is substantially the same as the distance 25 between the surface of the top 9 and the under surface of the board 15 is then removed from the board by withdrawing the pins 21 from the openings in the front edge thereof and is positioned between the top 9 and the under surface of the board 15 as shown in Figure 1. The board is thereby firmly and rigidly supported for use over the top 9 of 35 the cabinet.

The free end of the board may, of course, be strengthened when an exceptionally long board is desirable. The opening 17 is positioned in the embodiment shown at the front 40 left-hand corner of the board and the adjacent corner of the board is preferably rounded as shown at 22 to permit the desired pivotal movement of the same.

The front of the compartment 14 is preferably provided with a door 25 hingedly connected by suitable hinges 26 to the front edge of the shelf 13. One of the leaves of each of the hinges is secured to the shelf 13 and the other leaf to the door 25. Upon 45 swinging the ironing-board out of position for use and into the compartment 14, the door closes the front thereof preventing the accumulation of dust therein and giving the cabinet a finished appearance. When it is 50 desired to position the board for use over the top 9 the door 25 is opened, the board swung out into position and the block placed between it and the top 9.

I find it desirable to provide the cabinet

with a lamp socket 28 for the reception of a 60 suitable incandescent lamp 29. By using a double socket connector I am enabled to supply an electric iron 31 thru a conductor 30 without the inconveniences which result 65 when the socket is positioned in an inaccessible or remote place in the room.

The provision of a combination kitchen-cabinet and ironing-board; the mounting of the board to permit swinging the same into position over the top of the cabinet for use 70 and from position thereover when not in use and for preventing displacement of the board from the position into which it is swung when not in use, and the provisions for facilitating swinging of the board into 75 and out of position for use and for firmly and rigidly supporting the board over the top of the cabinet when in position for use are highly important aspects of my invention.

I do not intend to limit the invention to the details of the particular embodiment which I have elected to describe, as I am aware and contemplate that modifications and changes may be made within the scope 85 of the invention which is set out in the appended claims.

I claim:—

In combination, a base having a horizontal top, a cabinet structure supported over 90 the rear portion of said top, an ironing board pivoted in the cabinet structure and swingable horizontally into position longitudinally of the base and within the area of the cabinet structure and out across the top of 95 the base forwardly of the cabinet structure, said ironing-board being pivoted above the base top and lying thereover with a space between it and the base top when in position out over the same forwardly of the cabinet, 100 and a block detachably secured to one edge of said board and forming a grip for swinging same out into position for use over said top forwardly of the cabinet, said block being removable from the board and adapted 105 to be interposed between the board and top to bridge the space between the board and top and support the board thereon when in position out thereover, said block when in position in the space between the cabinet top 110 and the board relieving the binding imposed at the pivotal mounting of the board by pressure upon the board when in extended position out over the top forwardly of the cabinet.

In witness whereof, I hereunto subscribe my name this 15th day of June, 1922.

ANDREW JOHNSON STEWART.
